US0D1065998S

(12) **United States Design Patent** (10) Patent No.: **US D1,065,998 S**
(45) Date of Patent: ** *Mar. 11, 2025

(54) **BRACKET APPLIED TO A WINDOW TREATMENT**

(71) Applicant: **Lutron Technology Company LLC**,
Coopersburg, PA (US)

(72) Inventors: **Vladislav Pejic**, Allentown, PA (US);
David A. Kirby, Zionsville, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/914,605**

(22) Filed: **Oct. 19, 2023**

Related U.S. Application Data

(63) Continuation of application No. 29/828,652, filed on
Feb. 28, 2022, now Pat. No. Des. 1,006,611.

CLAIM

The ornamental design for a bracket applied to a window treatment as shown and described.

DESCRIPTION

FIG. 1 is a perspective view of a bracket applied to a window treatment showing our design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in an alternate position;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view of a second embodiment thereof;

FIG. 18 is another perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a perspective view thereof in an alternate position;

FIG. 26 is another perspective view thereof;

FIG. 27 is a front view thereof;

FIG. 28 is a rear view thereof;

FIG. 29 is a left side view thereof;

FIG. 30 is a right side view thereof;

FIG. 31 is a top view thereof; and,

FIG. 32 is a bottom view thereof.

The broken lines depict structure or features which form no part of the claimed design.
